(57) CLAIM

The ornamental design for a handheld transceiver with LCD display, as shown and described.

DESCRIPTION

FIG. 1 is the front top view of the remote control transceiver of our new design;

FIG. 2 is the back rear view of the remote control transceiver of our new design;

FIG. 3 is the top end view of the remote control transceiver of our new design;

FIG. 4 is the bottom end view of the remote control transceiver of our new design (note, there is a four tone shading of this end view because of the angle of the light on the unit (there are only 2 shades in the design, front and back));

FIG. 5 is the right side view of the remote control transceiver of our new design;

FIG. 6 is the left side view of the remote control transceiver of our new design; and,

FIG. 7 is the trimetric view of the remote control transceiver of our new design.
